UNITED STATES PATENT OFFICE.

EDWARD H. DOLDER, OF SERENA, ILLINOIS.

WASHING-MACHINE.

1,397,270.

Specification of Letters Patent. Patented Nov. 15, 1921.

Application filed March 31, 1920. Serial No. 370,072.

To all whom it may concern:

Be it known that I, EDWARD H. DOLDER, a citizen of the United States, residing at Serena, in the county of La Salle and State 5 of Illinois, have invented a certain new and useful Improvement in Washing-Machines, of which the following is a full, clear, concise, and exact description, reference being had to the accompanying drawings, forming 10 a part of this specification.

This invention relates to improvements in washing machines.

One object of the invention is to provide a machine for economically and efficiently 15 washing clothes and other textile fabrics and more particularly that type of washing machine wherein a pivotally mounted tub or vessel is employed adapted to be oscillated about its pivotal supports.

20 A more specific object of the invention is to provide a washing machine of the oscillating tub type wherein the articles being washed are subjected alternately to the force of the washing solution therethrough in one 25 direction and the drawing or draining off, in the opposite direction, of the washing solution, to thereby accelerate the removal of the dirt or other foreign matter.

In the drawing forming a part of this 30 specification, Figure 1 is a side elevation of a washing machine embodying my improvements. Fig. 2 is a vertical sectional view taken perpendicular to the pivotal axis of the tub or vessel. And Fig. 3 is a 35 vertical sectional view at right angles to the sectional view shown in Fig. 2, the section of Fig. 3 coinciding with the pivotal axis of the tub or vessel.

In said drawing, 10 indicates a standard 40 or mounting which may be of any suitable or desired form and 11 indicates the oscillating tub or vessel. The vessel 11 is pivotally mounted on the standard 10 by any suitable means such as the studs 12 which 45 are preferably formed integral with spider-like brackets 13 secured to the opposite ends 14—14 of the vessel. In the instance shown, the machine is adapted to be manually operated and for this purpose I provide a 50 handle 15 which may be seated at its lower end in a suitable socket 16 formed integral with one of the brackets 13. As will be understood by those skilled in the art, the machine is, of course, adapted to be mechanically operated by suitable mechanism. 55

In carrying out my invention, I preferably make the vessel 11 of suitable oval cross-section, as clearly indicated in Fig. 2, thereby providing curved bottom and side walls as indicated at 17. The vessel may 60 be made of any suitable material and preferably of galvanized iron or copper. The vessel is provided at the top thereof with a relatively large opening indicated at 18 through which the articles to be washed, the 65 water, soap, etc., are adapted to be introduced and the clothes or other articles removed. Surrounding said opening is a flange 19 indicated most clearly in Fig. 2, forming suitable guides for the extended 70 ends of a pin 20 carried by the cover which is preferably formed in two sections 21 and 22, pivotally jointed as indicated at 23, the section 22 being pivotally attached to the vessel 11 as indicated at 24. 75

On the interior of the vessel, I provide what may be termed two partitions indicated by the references A—A. The said partitions A—A are symmetrically disposed with respect to the axis of oscillation and 80 the same are extended from end to end of the vessel in lines parallel to the said axis. The partitions A extend from points 25 at the sides of the vessel which are at a level approximately one-half way between the 85 axis and the lowermost point of the vessel. The partitions are sloped slightly upwardly from the points 25 to the point indicated at 26 when a relatively abrupt curve is made in each partition as indicated at 27 and 90 thereafter the partitions extend vertically as indicated at 28. As clearly indicated in Fig. 2, the portions 28 of the partitions are separated an appreciable distance and their top edges terminate above the axis of oscillation. In actual practice, the partitions A will preferably be made of sheet metal and provided with a plurality of perforations or openings as indicated at 29, it being observed that said openings 29 are provided 95 in all parts of the partitions including the vertical sections 28 thereof, for a purpose hereinafter described. A removable cover 30 is provided to close the opening formed by the upper edges of the vertically extending sections 28 of the partitions. By removing the cover 30, it is evident that the operator may obtain access to the lower part of the tub for cleaning the latter out when desired. The water or other washing solu- 100 105 110

tion may be readily drained off from the tub by means of a suitable drain-cock indicated at 31.

With the arrangement shown, it will be seen that the partitions A divide the vessel 11 into what may be termed an upper compartment and a lower compartment, the upper compartment being appreciably larger than the lower compartment. Furthermore, 16 by extending the partitions vertically near the center of the vessel, as heretofore described, the upper compartment is divided into what may be termed two chambers, the upwardly extended parts of the partitions 21 forming, in effect, a hollow barrier or baffle which serves to keep the articles being washed divided into two separate batches.

In operating my improved machine, the clothes are introduced into the vessel on the 26 upper sides of the partitions and divided into two substantially equal batches, one on either side of the said barrier. Water with soap or other ingredients desired to facilitate the cleansing operation, is introduced 31 so as to reach a level corresponding approximately with the points 26. The vessel is oscillated first to one side and then to the other. During this action, it is evident that one batch of the articles being washed will 36 descend and the washing solution will rush through the perforations in the corresponding adjacent partition A and force itself through the articles. At the same time, the other batch of the articles is being elevated 41 and the washing solution will drain off therefrom through the other partition A. In the case of the batch of articles which is elevated, it is evident that the same will tend to fall on to the curved section 27 and section 28 of the corresponding partition and hence the washing solution will drain through these portions of the partition and will be permitted to fall back into the main body of the washing solution, thus facilitating the deposition of the dirt or other foreign matter in the bottom of the tub by sedimentation.

In actual practice, I have found that better results are obtained by permitting the 50 vessel to remain stationary for a very short interval at the end of each oscillation, as this gives the washing solution ample time to drain through and from the uppermost batch of the articles. This latter action, as I 55 have found from actual observation, appears to produce, in effect, a degree of suction or vacuum which greatly accelerates the cleansing of the clothes or other fabric articles and apparently draws the dirt from the 60 clothes or other articles, as contra-distinguished from a rubbing action.

I have described the partitions A as being "perforated" but this term is to be understood in a broad sense and not in the usual 65 restricted sense since it is evident that the

same results can be obtained by using partitions which may be made of other materials, so long as the said partitions are of such character as to properly sustain the clothes or other articles and prevent them from falling through and at the same time permit the passage of the washing solution readily therethrough from one side to the other. Various other changes and modifications will readily suggest themselves to those skilled in the art and all changes and modifications are contemplated that come within the scope of the claims appended hereto.

I claim:

1. In a washing machine having a suitable standard, the combination with a vessel having a smooth interior surface, said vessel being pivotally supported on said standard and adapted to contain the articles to be washed and the washing solution; of partitions within said vessel extending substantially parallel to the pivotal axis thereof, said partitions being provided with openings therein adapting a washing solution to pass therethrough, said partitions being arranged to divide the interior of the vessel into an upper compartment and a relatively smaller lower compartment, said partitions being also upwardly extended in spaced relation on opposite sides of the pivotal axis 90 near the center of the vessel to form a barrier and thereby divide the upper compartment into two portions, whereby the articles in each chamber are alternately subjected to immersion in and withdrawal from the 100 washing solution as the vessel is oscillated.

2. In a washing machine having a suitable standard, the combination with a vessel having a smooth interior surface, said vessel being of substantially oval cross section and pivotally mounted on said standard and adapted to contain both the articles to be washed and the washing solution; of partitions extending parallel to the pivotal axis of the vessel within the latter, said partitions having openings therein to permit passage of the washing solution therethrough, the partitions dividing the vessel into upper and lower compartments and having portions thereof extending upwardly in spaced relation on opposite sides of the pivotal axis 115 near the center of the vessel to thereby form a barrier in the upper compartment and divide the latter into two portions, said barrier extending above the said pivotal axis of the 120 vessel.

3. In a washing machine having a suitable standard, the combination with a vessel having an interior surface free from projections, said vessel being pivotally supported on said standard and adapted to contain the articles to be washed and the washing solution; of partitions having openings therein disposed within said vessel and extending substantially parallel to the pivotal axis 130

thereof, said partitions extending from points at the sides of the vessel disposed below said pivotal axis toward the median plane of the vessel and then upwardly to points above the said pivotal axis, said upwardly extended parts of the partitions being spaced whereby the upper part of the interior of the vessel is divided into two portions by a hollow barrier.

10 4. In a washing machine having a suitable standard, the combination with a vessel, said vessel being pivotally supported on said standard and adapted to contain the articles to be washed with the washing solution; of partitions having openings therein disposed within said vessel and extending substantially parallel to the pivotal axis thereof, said partitions extending from points at the sides of the vessel disposed below said pivotal axis toward the median plane of the vessel and then upwardly to points above the said pivotal axis, said upwardly extended parts of the partitions being spaced whereby the upper part of the interior of the vessel is divided into two portions by a hollow barrier; and a displaceable cover at the tops of said upwardly extended portions

of the partitions arranged to permit access to the interior of the vessel below said partitions.

5. In a washing machine having a suitable standard, the combination with a vessel, said vessel being pivotally supported on said standard and provided with an opening in the top thereof; of two partitions within said vessel arranged parallel to the pivotal axis thereof, each of said partitions extending substantially vertically downward from a point above the pivotal axis to a point therebelow and thence outwardly and downwardly to the side of the vessel, said partitions having openings therein to permit passage of the washing solution therethrough; and a closure for the opening formed between the uppermost edges of said partitions.

In witness that I claim the foregoing I have hereunto subscribed my name this 17th day of March, 1920.

EDWARD H. DOLDER.
